PUMP

Gunnar A. Wahlmark, Rockford, Ill.

Application February 27, 1936, Serial No. 66,009

12 Claims. (Cl. 103—126)

The invention relates to pumps and has as a general object to provide a rotary pump of novel and improved construction which is quiet and efficient in operation, compact and rugged in construction, and readily installed and adjusted.

A primary object of the invention is to provide a single stage rotary pump of novel and improved construction capable of running quietly and efficiently while operating at high vacuum and against high pressure.

Another object is to provide a pump having a single stage composed of rotary pumping elements, an intake port and a discharge port for the stage, an auxiliary reservoir receiving a portion of the liquid pumped, and an auxiliary inlet port disposed intermediate the regular ports and supplied with liquid from the auxiliary reservoir to fill completely the recess in the pumping elements and thus enable the pump to operate quietly when operating at high vacuum and against high pressure.

Yet another object is to provide a pump having a pressure actuated discharge control means and a bleed passage adjustable to vary the length of time after starting of the pump when the control means will permit discharge from the pump.

A further object is to provide in a pump a valve controlling the discharge from the pump, a piston for actuating the valve responsive to the pressure of the liquid discharged and having an annular undercut in its outer surface, and a bypass passage discharging through the undercut on the piston to a reservoir in the pump to maintain the piston lubricated and thereby assure ready response to the piston to changes in pressure.

Other objects and advantages will become apparent from the following detailed description taken in connection with the accompanying drawings, in which:

Fig. 1 is a vertical diametrical section of a pump embodying the features of the invention.

Fig. 2 is a partial transverse sectional view taken along line 2—2 of Fig. 1.

Fig. 3 is a partial transverse sectional view taken along line 3—3 of Fig. 1.

Fig. 4 is a partial transverse sectional view taken along line 4—4 of Fig. 1.

Fig. 5 is a partial transverse sectional view taken along line 5—5 of Fig. 1.

Fig. 6 is a fragmentary view showing the discharge control valve and piston in closed position.

Fig. 7 is a view like Fig. 6 showing the dis-

charge control valve and piston in the position assumed just prior to opening of the valve.

Fig. 8 is a similar view showing the valve in open position.

While the invention is susceptible of various modifications and alternative constructions, it is shown in the drawings and will hereafter be described in a preferred embodiment, but it is not intended that the invention is to be limited thereby to the specific construction disclosed, but it is intended to cover all modifications and alternative constructions falling within the spirit and scope of the invention as defined by the appended claims.

As shown in the drawings for purposes of disclosure, the pump is of the rotary type having an elongated casing comprising a horizontally disposed cup-shaped member 10, forming one end of the casing, within which is disposed a pump chamber proper and pressure actuated means controlling the discharge from the pump. Secured over the open end of the cup-shaped member 10 as by bolts 11 is an end closure 12 completing the casing and having an axial extension 12'. A gasket 13 is interposed between the cup-shaped member 10 and the end closure 12 to make the joint fluid-tight so that the casing in addition to housing the pumping and control means constitutes an auxiliary reservoir 14. Depending from the cup-shaped member 10 and removably secured thereto in fluid-tight relation is a strainer cup 15 within which is supported a double screen strainer 16.

As stated above, there is disposed within the casing a pump chamber proper. One end wall of the chamber is formed by the end closure 12, while the other end wall is formed by a plate 18 spaced from the end closure by an annular ring 19 constituting the periphery of the pump chamber. Housed within the pump chamber and operable to draw fluid into the chamber and forcibly discharge it therefrom are rotary pump elements of the general character disclosed and claimed in my copending applications Serial No. 675,218, filed June 10, 1933, and Serial No. 14,017, filed April 1, 1935, comprising an internally toothed rotor 20 rotatable within the annular ring 19. Positioned eccentrically within the rotor 20 and meshing therewith over a portion of the circumference only is a roller 21 and interposed in the space left by the eccentric mounting of the rotor and roller is a crescent-shaped element 22 completing the pump chamber. The axial dimensions of the rotor and roller are such that

5

20

25

30

35

40

45

50

55

the end faces have a sliding but fluid-tight engagement with the end walls of the chamber.

Here the roller 21 is the driving element and to that end is secured as by a key 25 to a shaft 26 journaled in the axial extension 12' and projecting outwardly thereof. To prevent leakage along the shaft, a collar 27 is secured to the shaft by a driving ring 28 and bears against an annular sealing member 29 of a rotary mechanical seal. The member 29 is secured to and suspended by a waterproof fabric diaphragm 29' disposed with its outer periphery in a recess 30 formed in an elongated housing 31 threaded into the end closure 12. The diaphragm is secured 15 in the recess by being clamped between shoulder 31' and an apertured cap 29'' forced into the recess by a nut 32 threaded into the recess. The cap 29'' is preferably formed of resilient metallic material and with a somewhat convex shape 20 adjacent the shaft so that the nut 32 engages the cap near its inner edge. Thus the cap compensates for any misalignment between the nut 32 and the shoulder 31' and serves automatically to take up any looseness caused by compression 25 of the diaphragm against the shoulder. A spring 32' urges the member 29 into contact with the collar 27. Preferably a gasket 33 is interposed between the housing 31 and the end closure 12.

Upon rotation, the pump elements operate in 30 well known manner to draw liquid into the pump chamber and forcibly discharge the same therefrom. To provide an intake passage for the pump chamber, the end closure 12 is formed with a radial bore 35 which is threaded at 36 35 for the reception of a conduit (not shown) leading to a supply reservoir. Extending laterally from the bore 35 is a passage 37 registering with a passage 38 in the cup-shaped member 10, discharging to the strainer bowl 15 to one side of 40 the strainer. Leading from the opposite side of the strainer is a duct 39 registering with a duct 40, in the end closure, communicating with the bore 35 radially inwardly of a ball 41 forced into the bore 35 to seal the passage 37 from the duct 45 40. The extreme inner end of the bore 35 communicates with a duct 42 (see Fig. 5) leading to an intake port 43 for the pump chamber completing the intake passage. Discharge from the pump chamber is through an exhaust port 45 and 50 a duct 46 in the plate 18 (see Fig. 2) and thence through a duct 47 formed in part in the plate 18, the annular ring 19 and the end closure 12 where it communicates with a threaded outlet 48. The outer end of the portion of the duct 55 47 in the plate 18 is closed by a ball 47' wedged into the duct.

Means is provided herein for controlling the lapse of time between starting of the pump and discharge of liquid from the casing and for effecting sharp cut-off in order to adapt the pump particularly for use with oil burners. To that end there extends axially from the plate 18 a cylinder 56 into which the duct 46 discharges. The cylinder is provided with a radial flange 57 and is secured in position by bolts 58 extending through the flange, the plate 18, and the annular ring 19 and threaded into the end closure 12 so as to secure all as a unit to the end closure. Slidable in the cylinder 56 is a piston 60 so as 70 to form with the plate 18 and the cylinder 56 a variable chamber 61 and to have its end exposed to the liquid discharged from the pump chamber through exhaust port 45 and duct 46. Carried in a bore 60' in the piston and having a limited 75 longitudinal movement relative thereto is a valve

62 having a tapered end for engagement with a valve seat 63 at the outer edge of a bushing 64 fixed in the plate 18 and communicating with the discharge duct 47. The piston is held against rotation by a pin 50 projecting from the plate 5 18 into a recess in the piston formed for that purpose.

Discharge from the pump casing takes place when the pressure in the chamber 61 is sufficient to move the piston 60 and the valve 62 in a 10 direction away from the plate 18 against the opposition of a compression spring 65 bearing at one end against the piston 60 and at the other end against a plate 66. The discharge pressure may be varied by adjusting the plate 15 66 longitudinally, which for that purpose is threaded onto the end of an elongated adjusting sleeve 67 extending through an aperture 68 in the closed end of the cup-shaped member 10 and held against outward movement by a bevelled 20 flange 67' thereon. The plate 66 is held against rotation by a bolt 69 which slidably engages in a notch 66' in the plate so that the discharge pressure may be readily varied by rotation of the sleeve 67 by the use of a suitable tool engaged in an end slot 67''. Concealing the outwardly projecting end of the sleeve is a cap 70.

For a purpose which will become apparent shortly, the valve 62 has, as stated above, a slight longitudinal movement relative to the piston 60. 30 To limit such relative movement in a direction toward the plate 18, the valve is formed with an annular flange 73 adapted to engage a shoulder 74 in the bore 60' of the piston 60. To limit movement of the valve relative to the piston in 35 the opposite direction, an adjustable stop 75 is threaded into the bore of the piston to be abutted by a reduced end 76 of the valve 62. Interposed between the adjustable stop and the flange on the valve is a compression spring 78 urging the 40 valve into engagement with the shoulder 74 of the piston. The stop 75 may be adjusted from the exterior of the casing by removal of the cap 70 and a plug 79 threaded into a bore 80 formed in the sleeve 67 for the purpose of giving access 45 to the stop 75 by a suitable tool.

For the purpose of supplying liquid to the auxiliary reservoir 14 and for the purpose of delaying actuation of the valve 62 after starting of the pump, an adjustable but constantly open 50 bleed passage is provided. To that end the valve 62 has a notch 85 increasing in depth as it approaches the tapered end of the valve and the piston 60 is formed near the corresponding end with an annular groove 86 forming with the 55 notch a variable bleed opening communicating with the chamber 61. The groove 86 communicates by means of a radial downwardly directed duct 87 with an annular undercut 88 in the outer surface of the piston. A portion of the pump 60 output discharged to the chamber 61 thus flows through the opening formed by the notch 85 into the annular passage 86, thence through the duct 87, the undercut 88 and out through an opening 89 in the top of cylinder 56 to the reservoir 14. 65

The size of the opening formed by the notch 85 may be varied by adjusting the stop 75 which determines the position of the valve relative to the piston 56 when the pump is idle, and thus permits a greater or lesser bleed of liquid from 70 the chamber 61. When the opening is large the pump must of course run for a greater period before sufficient pressure is built up in the chamber 61 to shift the piston in a direction to open the discharge passage controlled by valve 62. 75

and when the opening is small the pressure is built up shortly after starting of the pump. Upon shifting of the piston by the building up of pressure, a relative movement of the piston and valve, limited by abutment of the flange 13 with shoulder 74, takes place and as a result the bleed opening is closed slightly over its size when the pump is idle, but the opening is never completely closed so that there is a constant bleed around 5 the piston and into the auxiliary reservoir 14. There is also a second bleed or by-pass passage from chamber 61 to undercut 88 (Fig. 8) formed by a recess 89' in cylinder 56, which is uncovered when piston 60 is shifted to open valve 62. 10 There is thus a constant flushing of the undercut 88 making the piston readily responsive to the pressure in the chamber 61 and maintaining the reservoir 14 filled with liquid. The greater portion of the liquid discharged to the reservoir 20 flows through undercut 89'. Means is also provided herein for enabling the pump to operate quietly and efficiently at high vacuum and against high pressure. To that end an auxiliary intake port 92 is provided (see Fig. 25 2) located intermediate the intake port 43 and the discharge port 45 to supply liquid to the recesses in the pumping elements while they are in engagement with the crescent shaped member 22. The port 92 is supplied with liquid from the auxiliary reservoir 14 and communicates therewith near the bottom thereof through a passage 93 formed in the plate 18. The plate 18 is slightly smaller in diameter than the internal diameter of the cup-shaped member 10 in the plane of the plate so as to provide a space 94 by means of which the duct 93 opens to the reservoir. In this manner the recesses in the pumping elements, which are only partially filled when the pump is operating at 10 high vacuum, are completely filled by the liquid in the reservoir 14 and thus not only is the efficiency of the pump increased but the noise at the exhaust port resulting from the operation of the pump with only partially filled recesses 45 is eliminated. Any excess of liquid fed into the reservoir 14 over the quantity drawn from the reservoir through the auxiliary port 92 is returned to the main reservoir through an opening 95 in the top of the member 10 which is 50 above the level of the port 92. If there is a gravity feed to the pump the plug 96 in the bottom of the member 10 may be removed and the opening 95 closed and the return pipe dispensed with. 55 The operation of the pump is best understood from a consideration of Figs. 6, 7 and 8 which show the control means in the various positions assumed during the operation of the pump. When the pump is idle the control means is in 60 the position shown in Fig. 6. Valve 62 then is seated to close the discharge passage 47 and piston 60 has been urged toward the plate 18 by the spring 65 to an extent permitted by abutment of the stop 75 with the end 76 of the valve. This 65 position of the valve and the piston determines the original size of the bleed opening formed by notch 85 and groove 86 and this opening may be increased or decreased by rotation of the stop 75 whereby the relative position of the piston 70 is changed with respect to the valve. Upon starting of the pump, liquid is drawn through the intake passage and the intake port 43 and discharged through the exhaust port 45 and duct 46 into the chamber 61. The initial 75 discharge from the pump flows through the bleed

passage formed by notch 85, groove 86, duct 87, undercut 88 and opening 89 to the auxiliary reservoir 14. Not until some time after commencement of operation of the pump is a sufficient quantity of liquid discharged to build up a pressure in the chamber 61 overcoming the spring 65 and urging the piston 60 away from the plate 18 to the position shown in Fig. 7. Such movement of the piston is relative to the valve 62 with the effect that the bleed opening is reduced in 10 size and the continued discharge of liquid immediately forces the piston still farther away from the plate 18 and the shoulder 74 thereon engages the flange 13 on the valve and moves the same away from its seat to permit discharge 15 from the pump. The piston and valve are now in the position shown in Fig. 8 which is the position they retain during operation of the pump. In shifting to the position shown in Fig. 8, piston 60 has uncovered the recess 89' in cylinder 56, 20 thereby opening another passage leading from chamber 61 to reservoir 14 by way of the undercut 88 in piston 60. The delay between the starting of the pump and the discharge of liquid from the casing may be varied by varying the size of 25 the bleed opening and such variation in the delay is effected simply by rotation of the stop 75. Similarly the pressure at which the valve opens to permit discharge may be varied by the rotation of the sleeve 61. 30

Should the pump be operating at such high vacuum that the recesses in the pumping elements are not completely filled, the auxiliary inlet port 92 comes into operation to supply an additional quantity of liquid completely filling the 35 recesses. This liquid is drawn from the auxiliary reservoir 14 which is constantly supplied through the bleed and by-pass passages. By filling the recesses in this manner the pump with but a single stage operates as efficiently and quietly at 40 high vacuum and against high pressure as a double pump. 45

When the pump is stopped the piston and the valve immediately move toward the plate 18 maintaining the liquid in the chamber 61 under full pressure until the valve is seated so that a sharp cut-off and a final discharge under full pressure are obtained. The parts of the control means now are again in the position shown in Fig. 6. 50

I claim as my invention:

1. A rotary pump comprising, in combination, a casing providing an auxiliary reservoir, means within the casing forming a pump chamber, rotary pumping elements housed in the chamber comprising a rotor and a roller disposed eccentrically within the rotor and meshing therewith over a portion of its circumference only, a crescent-shaped member interposed between said elements in the space formed by the eccentric mounting thereof, an intake passage for the pump chamber including an intake port disposed on one side of the point of engagement of said pumping elements, a discharge passage including a discharge port disposed on the opposite side of the point of engagement of said elements, a drive shaft for rotating said elements, said elements being operable upon rotation to draw liquid into the pump chamber and forcibly discharge the same therefrom, a passage for conducting a portion of the liquid discharged from the chamber to the auxiliary reservoir in the casing, and an auxiliary intake port for the pump chamber disposed intermediate the intake and exhaust ports and supplied with liquid from the auxiliary 55 60 65 70 75

reservoir to compensate for any deficiency at the intake port when the elements are operating at high vacuum and against high pressure.

2. A rotary pump comprising, in combination, 5 a casing providing an auxiliary reservoir, an overflow opening for the reservoir in the casing, means within the casing forming a pump chamber, rotary pumping elements housed in the chamber comprising a rotor and a roller disposed eccentrically within the rotor and meshing therewith over a portion of its circumference only, a crescent-shaped member interposed between said elements in the space formed by the eccentric mounting thereof, an intake passage for the 10 pump chamber including an intake port disposed on one side of the point of engagement of said pumping elements, a discharge passage including a discharge port disposed on the opposite side of the point of engagement of said elements, a 15 drive shaft for rotating said elements, said elements being operable upon rotation to draw liquid into the pump chamber and forcibly discharge the same therefrom, a passage for conducting a portion of the liquid discharged from the chamber to the auxiliary reservoir in the casing, an auxiliary intake port for the pump chamber disposed substantially diametrically opposite the point of engagement of said elements, and a duct 20 communicating at one end with said auxiliary port and at the other end communicating with the auxiliary reservoir near the bottom thereof, said auxiliary port being disposed below the overflow opening in said casing.

3. A pump comprising, in combination, means 35 forming a pump chamber having an intake port and a discharge port, pumping elements housed in the chamber operable to draw fluid thereto and forcibly discharge fluid therefrom and into a valve chamber, valve means responsive to the pressure of the fluid in the valve chamber 40 controlling discharge from the valve chamber, an open internal bleed passage from said valve chamber, and adjustable means carried on said valve means and accessible from outside the valve 45 chamber for varying the size of the bleed passage to vary the delay in the discharge from the pump after initiation of operation of the pump.

4. A pump comprising, in combination, means forming a pump chamber, means including a piston 50 subject to a pressure differential forming a variable chamber, an intake passage for the pump chamber, a discharge passage communicating at one end with the pump chamber and at the other end with the variable chamber, pumping elements 55 in the pump chamber operable to draw fluid into the pump chamber and forcibly discharge the same therefrom, a valve carried by said piston controlling the discharge from said variable chamber, said valve being yieldably retained seated until a predetermined pressure is attained in 60 the variable chamber, a bleed passage leading from said variable chamber directly to the low pressure side of the piston to delay discharge from the chamber after initiation of operation 65 of the pump, and means carried on said piston for adjusting the bleed passage.

5. A pump comprising, in combination, means forming a pump chamber, means including a pressure actuated piston forming a variable chamber, an intake passage for the pump chamber, a discharge passage leading from the pump chamber to the variable chamber, pumping elements 70 in the pump chamber operable to draw fluid into the chamber and forcibly discharge the same 75 therefrom, a valve carried by said piston control-

ling the discharge from said variable chamber, means maintaining said valve seated to prevent discharge until a predetermined pressure is attained in the variable chamber, a bleed passage communicating with the variable chamber 5 through an opening formed intermediate the valve and the piston to delay actuation of the piston, and adjustable means varying the relative position of said valve and piston to vary the size of the bleed opening.

6. A pump comprising, in combination, means forming a pump chamber, means including a pressure actuated piston forming a variable chamber, an intake passage for the pump chamber, a discharge passage communicating at one end with the pump chamber and at the other end with the variable chamber, pumping elements in the pump chamber operable to draw fluid into the chamber and forcibly discharge the same therefrom, a valve carried by said piston controlling the discharge from said variable chamber, said valve being movable relative to said piston, a bleed passage communicating with said variable chamber comprising an annular groove in the piston and a notch of varying depth formed in said valve 20 opposite the groove, and means for adjusting the position of said valve relative to said piston to vary the size of the bleed opening formed by the notch 25 in the valve and the piston.

7. In a pump having pumping elements, discharge control means comprising means including an axially movable piston forming a variable chamber receiving the fluid discharged by the pumping elements, said piston being movable to vary the capacity of the chamber, a valve carried by 35 said piston controlling the discharge from the variable chamber and operable upon the creation of a predetermined pressure in the chamber to permit discharge therefrom, a bleed passage 40 communicating with the variable chamber and controlled by said valve and including an annular undercut in the periphery of said piston, and means for adjusting the valve relatively to the piston to vary the bleed passage.

8. In a pump having pumping elements, discharge control means comprising means including an axially movable piston forming a variable chamber receiving the fluid discharged by the pumping elements, a valve carried by said piston and movable axially relative thereto controlling the discharge from the variable chamber and operable upon the creation of a predetermined pressure in the chamber to permit discharge therefrom, and a bleed passage communicating with the variable chamber comprising a notch in the 55 valve, a groove in the piston opposite the notch and forming therewith a variable bleed opening, a radial duct leading from the groove, and an annular undercut in the periphery of the piston to which the radial duct discharges.

9. In a pump having pumping elements, discharge control means comprising means including a horizontally disposed cylinder and an axially movable piston therein forming a variable chamber receiving the fluid discharged by the pumping elements, a discharge passage leading from the variable chamber, an axial bore in said piston providing a shoulder, a valve for controlling the discharge passage disposed in the bore in said piston having an annular flange adapted to 70 engage the shoulder in the bore to limit movement of the valve relative to the piston in one direction, a stop threaded into the bore of the piston to limit movement of the valve in the opposite direction, a compression spring interposed 75

- between the stop and the valve to urge the valve into engagement with the shoulder in the bore, said stop being adjustable to vary the relative position of the valve and piston, a bleed passage 5 communicating with the variable chamber comprising a notch of varying depth in the valve, a groove opening into the bore of the piston opposite the notch to form therewith a bleed opening variable by adjustment of the stop, a downwardly directed duct leading from the groove in the piston, an annular undercut in the periphery of the piston to which the duct discharges and an aperture in the top of the cylinder communicating with said undercut, and a compression spring 10 urging said piston in a direction to reduce the size of the variable chamber and to seat the valve.
10. A pump comprising, in combination, a casing providing an auxiliary reservoir, means within the casing forming a pump chamber, means including an axially movable piston forming a variable chamber, an intake passage for the pump chamber including an intake port, a discharge passage leading from the pump chamber to the variable chamber, a discharge port from the variable chamber, rotary pumping elements disposed in the pump chamber operable upon rotation to draw liquid through the intake passage and discharge the same forcibly through the discharge passage, a bleed passage communicating with the variable chamber and discharging to the auxiliary reservoir, said bleed passage being constantly open, a valve device adjustably mounted on said piston and operable to control the discharge of liquid from the variable chamber both through the discharge port and the bleed passage, and an auxiliary intake port for the pump chamber supplied with liquid from the auxiliary reservoir. 15
11. A rotary pump comprising, in combination, a casing providing an auxiliary reservoir, means within the casing forming a pump chamber proper, means including an axially movable piston forming a variable chamber, rotary pumping elements disposed in the pump chamber comprising a rotor and a roller mounted eccentrically therein and meshing therewith over a portion of its circumference only, a crescent-shaped member interposed between the rotor and roller in the space formed by the eccentric mounting thereof, 20 an intake passage for the pump chamber including an intake port, a discharge port communicating with the variable chamber, said pumping elements being operable upon rotation to draw liquid into the pump chamber and forcibly discharge the same into the variable chamber, a discharge passage leading from the variable chamber, a valve carried by said piston controlling the discharge passage, a compression spring urging said piston in a direction to close the valve, a permanently open bleed connection leading from said variable chamber to the auxiliary reservoir, and an auxiliary intake port disposed intermediate the intake and discharge ports of the pump chamber supplied with liquid from the auxiliary reservoir. 25
12. A pump comprising, in combination, means forming a pump chamber, means including a cylinder and a piston movable axially in the cylinder forming a variable chamber, an intake passage for the pump chamber, a discharge passage leading from the pump chamber to the variable chamber, pumping means within the pump chamber operable upon actuation to draw liquid into the pump chamber and forcibly discharge the same therefrom, a valve carried by said piston controlling the discharge from the variable chamber, said piston being shiftable upon the creation of a predetermined pressure in the variable chamber to move the valve to permit discharge from the variable chamber, and a bypass passage including an annular undercut in the periphery of said piston and an undercut in said cylinder communicating with the undercut in the piston and uncovered upon shifting of the piston to valve-open position to effect communication of the undercut with the variable chamber. 30
